UNITED STATES PATENT OFFICE.

ANDREW M. COYLE, OF NEW YORK, N. Y., ASSIGNOR TO OTIS ELEVATOR COMPANY, OF JERSEY CITY, NEW JERSEY, A CORPORATION OF NEW JERSEY.

MOTOR CONTROL.

974,238.

Specification of Letters Patent. Patented Nov. 1, 1910.

Application filed January 30, 1908. Serial No. 413,473.

To all whom it may concern:

Be it known that I, ANDREW M. COYLE, a citizen of the United States, residing in New York, in the county of New York and State of New York, have invented a new and useful Improvement in Motor Controls, of which the following is a specification.

My invention relates to a system of control for electric motors, particularly those used for hoisting and lowering theater curtains, but it may have a general application.

An object of my invention is the provision of improved means for controlling the speed of operation of the respective units of a multiple curtain hoisting apparatus which lifts and lowers curtains at the same time.

A further object is the provision of means for controlling the operation of electric motors, wherein one motor is used for hoisting and another motor is used for lowering, also means for varying the relative speeds of the hoisting and lowering motors.

Other objects of my invention will appear hereinafter, the novel combinations of elements being set forth in the appended claims.

In the accompanying drawings, Figure 1 represents a wiring diagram of my control system, wherein a single motor is used for both hoisting and lowering; Fig. 2 is a wiring diagram in which there are two motors, one for hoisting and one for lowering. Figs. 3 and 4 represent the hoisting apparatus adapted to the systems of control shown in Figs. 1 and 2 respectively; Figs. 5 and 6 illustrate a preferred form of stop-motion apparatus shown in plan and side views respectively.

Similar reference characters designate similar parts in both figures.

The principal features of the particular form of hoisting mechanism to which my improved system of motor control is especially adapted are disclosed in my co-pending application, Serial No. 397,310, filed October 14, 1907 Patent No. 959,999, May 31, 1910, for an improvement in curtain hoisting apparatus.

Briefly described, the hoisting apparatus to which my invention is particularly adapted, is illustrated in Figs. 3 and 4, and comprises a motor 80 upon whose shaft 93 is secured, at regular intervals, a series of friction driving members or disks, such as 94 adapted to coöperate with other friction

driven members, such as 95, which latter are geared to suitable hoisting drums as 96. Each friction driving disk and co-operating driven mechanism and hoisting drum comprises a single unit of a multiple hoisting apparatus. While the number of such units may be as many as desired, for purposes of illustration I show in Figs. 1 and 2 of the present drawings controlling systems for a multiple hoisting apparatus having six hoisting drums or units, and adapted to control the hoisting and lowering of six theater curtains or other apparatus. The friction wheels 94 and 95 which are geared to their respective hoisting drums, are pivotally mounted so that they may be independently raised out of or lowered into engagement with their respective friction driving disks upon the motor shaft. Each hoisting unit is provided with a brake shoe 99 which coöperates with the friction wheel 95 driven by the disk 94 upon the motor shaft, and this brake shoe is so arranged that the brake is applied and the friction wheel is raised out of engagement with the driving means simultaneously. This operation is effected by means of a separate electro-magnet as 62 for each hoisting unit, and throughout this specification this magnet will be referred to as the brake magnet. The brake spring tends to hold the shoe 99 in engagement with the friction wheel 95 except when the brake magnet 62 is energized. Each unit is also equipped with an additional electro-magnet as 63 which I call a tripping magnet, and which is so arranged that when the same is properly energized and the brake magnet is also energized, the parts are in proper position to effect a raising of the load. If, however, the brake magnet is energized and the tripping magnet is deenergized or does not receive current, the brake will be released, but the tripping apparatus controlled by the tripping magnet will prevent the friction driving wheel from engaging the driving disk upon the motor shaft, and the hoisting drum is in a position to be turned backward by means of the unbalanced load. The apparatus to which the controlling system shown in Fig. 1 is especially applicable has, furthermore, a number of gear wheels such as 100; one for each hoisting unit, each of which is geared directly to its respective hoisting drum and which is connected 110

through a clutch mechanism to a sprocket wheel 101 which in turn is connected by a sprocket chain 102 to a smaller sprocket wheel 103 rigidly mounted upon the motor shaft. This clutch mechanism is so arranged that when the hoisting drum is raising a load, or when the brake is applied and the drum at rest, it does not come into operation, but as soon as the unbalanced load tends to drive the hoisting drum backward, the clutch at once operates and operatively connects the hoisting drum to the motor shaft and the speed of descent of the load depends upon the speed of rotation of the motor. Thus, while the motor always runs in one direction, the speeds of hoisting and lowering are both dependent upon the motor speed.

The apparatus particularly adapted to the controlling system shown in Fig. 2, is illustrated in Fig. 4 and is similar in every respect to the foregoing description, but with this one exception: The gear 100 meshing with the hoisting drum and connected through a clutch mechanism to the hoisting motor, is in this instance designated by 100' and is connected through a similar clutch mechanism to the shaft 93' of an additional motor 80' which is only used for lowering. Each motor therefore, performs its separate function of hoisting and lowering, and as the relative speeds of these motors may be varied at will, the relative speeds of hoisting and lowering may be adjusted to any desired speed, and thus, in the particular case of theater curtain control, many and varied scenic effects may readily be produced with facility and despatch.

Each hoisting drum is provided with a limit switch or stop-motion apparatus which is operated by the hoisting drum through gearing and serves automatically to slow down and stop any of the hoisting drums at either the upper or lower limit of curtain travel.

The stop-motion apparatus may be mounted in a housing 104 on top of the machine and operated by gear wheels 105 respectively in mesh with the gear wheels 106 of the hoisting units. The purpose of the stop-motion apparatus is to operate circuit-breakers so as to deenergize the electro-magnet 62, and to also slow down the motor a short time prior to the deenergization of the brake electro-magnet. It is to be understood that for each unit of the multiple hoisting apparatus there is a corresponding unit of the stop-motion apparatus, and that when a stop-motion unit operates to open its circuit closer only the corresponding unit of the multiple hoisting apparatus will be effected. This operation is automatic, as will be more fully explained hereinafter.

Referring now more particularly to Figs. 5 and 6 where is shown a preferred form of

my improved stop-motion apparatus adapted to a hoisting machine having any desired number of units, it will be seen that I have provided a base 107 for the stop-motion apparatus, which base may be bolted to the frame 108 of the hoisting apparatus shown in Figs. 3 and 4. A rectangular frame 109 is secured to the base 107 and projecting upwardly from its opposite rear corners are integral bracket arms or bearing standards 75 110 and 110' which support a rod 111 upon which are loosely mounted swinging arms 112 and 112'. Between these arms is a bushing 113 on the rod 111; the purpose of said bushing being to hold the arms 112 and 112' 80 spaced apart and in their proper positions. The gear wheel 105 which is driven by the gear 106 of a hoisting unit is secured to a shaft 114 which carries a small pinion 115. The latter extends the entire length of the 85 shaft 114. Mounted on the frame 109 and parallel with the shaft 114 is a screw threaded shaft 116 which is held stationary by its supports. Mounted on the shaft 116 are two gear wheels 117 and 117' whose hubs are 90 screw-threaded to correspond with the threads on the shaft 116. On the hub of the gear wheel 117 are two cams 118 and 119, and on the hub of the gear wheel 117' are two similar cams 118' and 119'. A rock-shaft 120 is journaled on the base 107 and rigidly secured thereto are rock-arms 121 and 122 which have at their outer extremities lateral projections 121' and 122' respectively, which are arranged to be engaged by 95 the cams 118' and 118, respectively. The cams 119 and 119' are arranged to engage the detents or trips 123 which are carried by the arms 112 and 112'; the latter each carry bridging members 57 and 58 to electrically 105 connect the contacts 59 and 61.

The operation of the construction shown in Figs. 5 and 6 is as follows: When the hoisting mechanism shown in Figs. 3 and 4 is in operation, the gear wheels 117 and 117' 110 of the stop-motion device are rotated by means of the gear connections above described. This rotation will impart to the gears 117 and 117' a lateral movement, owing to their threaded engagement with the shaft 116. If it be assumed that the gear wheel 117 is rotated in a counter-clockwise direction when looking at it from the right, then said gear wheel will move toward the right-hand end of the shaft 116, the threads on 115 the shaft 116 being right-handed. As the gear wheel 117 approaches its limit of travel to the right, the smaller cam 118 will first engage the lower surface of the lateral projection 122' on the arm 122 of the rock-shaft 120, lifting said arm and partially rotating the said rock-shaft and thereby effecting the opening of the slow-down switch 46 as hereinafter described. The large cam 119 which projects a less distance to the right than the 120

cam 118 will next engage the detent 123 on the arm 112, thus lifting the latter with its contact plate 57 and breaking the electrical connection between the contacts 59 and 59'.

5 It will be observed that the lateral surfaces of the cams 118 and 119 are inclined or spiral in form and of the same pitch as the threads on the shaft 116. This is for the purpose of preventing any lateral or side 10 thrust of the cams against the parts they engage. This inclination of the cams corresponds to the pitch of the threads on the shaft 116, so that the forward movement of the cam 119, for example, as it approaches 15 the lug 123, is just equal to the receding movement due to the inclined surface of the cam, and the lug 123 will therefore not be engaged until the end of the cam rides under it, lifting the arm 112. The slow-down 20 switch 46 is arranged to be operated by the rotation of the rock-shaft 120 every time one of the hoisting drums approaches its limit of movement in either direction.

Referring to Fig. 1, 80 designates the 25 motor which is used for both hoisting and lowering, and which always runs in one direction. The motor receives current from the positive and negative mains (designated + and —, respectively) connected to a suitable source of current supply. 1 and 2 are the magnets which operate, when energized, to close a circuit to the motor 80. 8, 9, 10 and 11 are sections of the motor starting resistance, which sections are controlled by 30 the electro-magnets 12, 13, 14 and 15, respectively. Other sectional resistances 20, 21 and 22 are arranged to be connected in parallel to the motor armature and are controlled by the magnets 26, 27 and 28, respectively. 40 48 is the magnet winding of a slow-down switch which is controlled by a mechanically operated switch 46. 33 designates a manually operated speed controlling switch, by means of which the speeds of 45 hoisting and lowering are determined. 31 is the fast speed magnet, and 29 is a magnet which operates to prevent the brake being raised when the motor 80 is at rest. The switch 45 is for the purpose of rendering the 50 speed controlling switch 33 inoperative whenever desired. 62, 62', etc., designate brake magnets for the various hoisting units, while 63, 63', etc., are the corresponding trip magnets. 57 and 58 are the mechanically 55 operated limit stops, 57 being the up limit and 58 the down limit for a single unit. The other units have similar limit switches, as 57', 58', etc. 64 and 65 each designate a series of selective push-buttons, six up buttons 60 and six down buttons, and all of these buttons are what are known as self-holding buttons, in that when pressed they are held in this position against the action of a spring or equivalent means by an electro-magnet. 65 In the system shown there are six up buttons

and six down buttons, and the operation of these buttons determines the particular hoisting unit which is to be operated either to raise or lower its load, depending upon the particular button operated.

70

The operation of the system of electrical control is as follows:—Any one of the buttons 64 or 65, or more than one, may be pushed, but for the purpose of illustration we will assume that the right hand button 75 65 is pushed against the action of the spring 66. It will be observed that the upper magnet windings 69, etc., of both the up and down buttons are all connected in series, and, furthermore, they are directly connected by 80 the wire 60 to the — main, and are also connected through the normally closed contacts 55 directly to the + main. These push-button magnet coils therefore receive current directly from the main line through 85 the contacts 55 and are thus energized, and, while the magnet coil of any one button is not of sufficient strength to automatically operate the push-button, it has the necessary 90 power to hold the push-button in closed position after the same has been manually pushed. This button having been pushed, the contacts 72 are brought into electrical engagement with each other and are held in this position against the action of the 95 spring 66. The hoisting drum corresponding to the button just operated is now in proper relation to hoist its load. The next operation is to move the lever 34 of the 100 manually operated speed switch 33 to the right until the switch lever 34 electrically connects the fixed segmental contacts 43, 42 and 35, the position of slow speed. This operation closes a circuit which is as follows:—From the + main at the junction 105 point 77 to and through the magnet 1, wire 81, magnet coil 2, magnet coils 29 and 31, wire 82, contact 42, switch lever 34, contact 43, switch 45, and by wire 60 to the — main at the junction 79. A parallel circuit 110 is also closed at the same time from the contact 42, switch lever 34, contact 35, contact 51, the bridging contact 50, and by the wire 83 to the — main at the junction 78. By thus closing a circuit through the magnet 115 coils 1, 2, 29 and 31 in series, the same become energized and operate to close the contacts associated therewith, namely, the contacts 6, 7, 30 and 32, respectively. A circuit is now closed to the motor armature through 120 the contacts 6 and 7 including the sectional starting resistances 8, 9, 10 and 11. At the same time a circuit is closed to the motor field winding 4, this circuit being from the + main at the junction 84, magnet winding 125 54, motor field 4, wire 85, contacts 32, wire 86, and so to the — main by way of contacts 7. The motor 80 is now enabled to start, the current flowing to the armature being limited by the sectional starting resistances 130

8, 9, 10 and 11 in series therewith. Upon closing the contacts 6 and 7 a circuit is established through the slow-down limit switch 46 and the magnet coil 48, and the latter becomes energized to raise the contact plate 52 into electrical engagement with the stationary contacts 53, also the contact plate 50 out of engagement with the fixed contacts 49 and 51. This opens the parallel circuit before mentioned through the magnet coils 1, 2, 29 and 31 from the contact 42, switch lever 34, contacts 51, 50, and wire 83 to the — main. The circuit to these magnets remains completed, however, through the contacts 42 and 43 as before pointed out.

The magnets 26, 27 and 28 are connected in series, and at this time are connected across the motor armature, the circuit being as follows:—From the motor brush 3, wire 87 and normally closed contacts 56, through the magnets 28, 27 and 26 to the contact 35 of switch 33, contact 43, switch 45, wire 60, contacts 7 to the motor brush 3'. At the moment of starting the motor from a position of rest, the voltage across the motor brushes 3 and 3' is at a minimum, which voltage increases as the motor increases in speed, due to the C. E. M. F. of the revolving armature, and, since the magnets 26, 27 and 28 are connected across the motor brushes, the current flowing in these magnets is proportional to the brush voltage of the motor. If the motor is heavily loaded upon starting, the voltage across the armature brushes will remain relatively low, due to the fact that the motor will run at a low speed with consequent low C. E. M. F., the greater part of the drop of potential taking place across the starting resistances 8, 9, 10 and 11. With the present conditions, however, since but a single unit is hoisting, the load is comparatively light and the voltage across the motor armature soon rises to a point sufficiently great to effect the operation of the magnets 26, 27 and 28. The operation of the magnet 28 closes the contacts 25, which connects the resistances 20, 21 and 22 in parallel to the motor armature. The magnet 27 operates to short-circuit the resistance 22, leaving the resistances 20 and 21 in parallel to the armature; while the magnet 26 short-circuits the resistance 21, thereby leaving the resistance 20 alone across the armature, and under no conditions in this resistance 20 ever short-circuited. The conditions at this time are for slowest speed, that is, the resistance in series with the motor armature is at a maximum, the field strength is also at a maximum, and the resistance in parallel with the armature is at a minimum.

At substantially the same time that the motor receives current by the operation of the magnets 1 and 2, the magnet 29 which is included in the circuit of these magnets closes a circuit from the + main through

the brake magnet 62 of the hoisting unit corresponding to the button pressed, by wire 88, brake magnet 62, tripping magnet 63, the contacts 59 of the up limit 57, wire 89, push-button magnet 71, button contacts 72, contacts 30 and to the — main at the point 78. The magnet 71 assists the magnet 69 in holding the push-button in operative position. The brake magnet and tripping magnet being both energized at this time, the hoisting apparatus is in proper condition to effect the raising of the load as before pointed out. The magnet 54, it will be remembered, is included in the circuit of the motor field winding 4, and the same current passes through both. Since the current in the motor field 4 does not instantaneously rise to its full value as soon as its circuit is closed, due to the self-induction of the field winding, the magnet 54 does not immediately operate to separate the contacts 55 and thus break the circuit through the upper magnet windings 69 of the series of push buttons. This arrangement insures that the lower magnet winding 71 of the operated push-buttons will become fully energized by the operation of the magnet 29 before the magnet 54 has operated to open the circuit of the upper push-button windings, and the push-button remains in its operative or closed position.

The switch lever 34 is next moved until it passes onto contact 36 and off of contact 35. The circuit to the magnet 26 is now opened at the contact 35, but the circuit to the magnets 27 and 28 is still closed through the contact 36. The magnet 26 therefore becomes deenergized and opens the contacts 23, inserting the resistance 21 in the parallel circuit to the motor armature. This increase in resistance across the armature circuit results in an increase in motor speed. Upon further movement of the switch arm 34 onto contact 37, the circuit to the magnet 27 is opened at the contact 36, while the magnet 28 alone remains energized. The circuit across the armature now includes the resistances 20, 21 and 22 and the motor further increases its speed. The lever 34 is now moved onto contact 38 and off of contact 37. This opens the circuit to the magnet 28 at the contact 37, causing the same to open its contacts and thereby opening the parallel circuit to the armature at the contacts 25 and the motor further increases its speed. Since the switch arm 34 now rests upon the contact 38, the magnet 12 including the resistance 74 is connected across the motor armature, this circuit being traced as follows:—From the motor brush 3, wire 87, contacts 53 (these latter being in electrical engagement with each other at this time), through the magnet winding 12, wire 68, resistance 74, contacts 38 and 43, switch 45, wire 60, contacts 7, and to the armature brush 3'. The magnet 12 now receives cur-

rent at the same potential as that of the motor armature and it will become energized to close the contacts 16, thereby short-circuiting the sectional starting resistance 8, 5 and the motor receives more current with further increase of speed. The next movement of the lever 34 carries it onto contact 39 and off of contact 38. Both magnets 12 and 13, together with the resistance 75, are 10 now connected across the motor armature and the magnet 13 operates to short circuit the sectional starting resistance 9 while the magnet 12 remains energized and maintains a short circuit across the sectional starting 15 resistance 8. The motor now runs still faster with but one-half of the starting resistance in circuit.

When the magnet 13 operated to close the contacts 17, the contacts 56 were separated 20 at substantially the same time, thus preventing any possible circuit to the magnets 26, 27 and 28 through the wire 70 as long as the magnet 13 is energized. The switch arm 34 next moves onto contact 40, thereby energizing 25 the magnet 14 through the resistance 76, thereby cutting out or short-circuiting the sectional resistance 10. The switch arm is now moved onto contact 41 which completes a circuit through the magnet 15 which operates 30 to short-circuit the remaining starting resistance 11. The ohmic resistance of each of the resistances 74, 75 and 76 is so proportioned that the current strength in any one of the magnets 12, 13, 14 or 15 is the same 35 for the same motor potential whether one magnet alone is in circuit or all of the magnets; that is to say, the ohmic resistance of the resistance 74 is equivalent to three times that of any one of these magnets, that of the 40 resistance 75 to twice the magnet resistance, while that of resistance 76 is the same as the resistance of one of the magnets. These magnets 12, 13, 14 and 15 are preferably so arranged that should the switch arm 34 be 45 rapidly moved from its initial position to the contact 41, the magnets will respond to the rise of motor potential as the same speeds up and will operate successively in prearranged order so as to short-circuit the sectional 50 starting resistances in proper order. This may be accomplished in one of several ways well known in the art and needs no further description. The motor now receives current at full line potential with 55 maximum field strength and assumes a speed to correspond therewith. The switch arm is next moved until it rests upon the segmental contacts 41, 44 and 43. The circuit to the magnets 12, 13, 14 and 15 remains unbroken, 60 but a circuit to the magnet 31 is opened through the wire 82 at the contact 42. The circuit including the magnet 29 is not interrupted, however, since an additional circuit is closed through the contact 44 and resistance 65 73, which resistance is now substituted

for the magnet 31. The magnet 31 now becomes deenergized and the contacts 32 controlled thereby move out of electrical engagement with each other. This results in placing the resistance 5 in series with the 70 motor field winding 4, since the short-circuit heretofore maintained across the resistance 5 by the contacts 32 and wires 85 and 86 is now opened through the separating of these contacts. By thus inserting the resistance 5 into the motor field circuit, the current flow in the latter is reduced, the field strength is therefore weakened, and the motor and connected hoisting unit run at full speed. As the load carried by this hoisting 80 unit approaches its upper limit of travel, the mechanically operated slow-down switch 46 which is operated every time one of the hoisting drums approaches its limit of movement in either direction, opens the circuit to the magnet 48 at the contacts 47. This magnet at once becomes deenergized, causing the contact plate 52 to move out of engagement with the contacts 53, and the contact plate 50 to electrically engage the 90 contacts 49 and 51. This operation opens the circuit to the magnets 12, 13, 14 and 15 at the contacts 53 and the entire starting resistance is re-inserted into the armature circuit, while the contacts 56 are once more 95 placed in electrical contact with each other. The deenergization of the magnet 48 also connects the contacts 49, 50 and 51 together, thereby closing two circuits, one of which is from the motor brush 3, wire 87, contacts 56, 100 wire 70, magnets 28, 27 and 26, wire 91, contacts 51 and 50, wires 83 and 92, contacts 7, to the motor brush 3'; the other circuit is from the right-hand terminal of the motor field winding, wires 85 and 90, contacts 49 105 and 50, wires 83 and 92, to the — main. The first-named circuit effects the operation of the magnets 26, 27 and 28, which will operate to connect the resistance 20 across the armature. The second-named circuit effects 110 the short-circuiting of the resistance 5, both terminals of which are now connected to the — main and the motor field strength is again at a maximum. The effect of these operations is to slow the motor down to extreme slow speed. The hoisting unit has at this time raised the load to its upper limit and the mechanically operated limit switch 57 automatically operates to open the circuit through the brake magnet 62, tripping magnet 63, and push-button magnet 71. The hoisting drum of the unit corresponding to the push-button operated now comes to rest and the spring 66 returns the button 115 to its initial position as shown on the drawing. The motor continues to run, however, at reduced speed until the slow-down mechanism operates to electrically connect the contacts 47, thereupon the magnet 48 is 120 again energized and the proper circuits are 125 130

established to the magnets 12, 13, 14 and 15 and the circuit through the magnets 26, 27 and 28 is opened, while the short-circuit around the field resistance is removed and the motor automatically runs up to full speed.

Should it be desired to operate two or more hoisting units at the same time, the push-buttons corresponding to the desired hoisting units may be pressed, after which the motor is started and run up to speed by the switch 33. The slow-down switch 46 operates automatically to slow the motor as any one of the hoisting units nears its limit of travel, after which the limit stop corresponding to such hoisting unit which has reached its limit of travel operates to bring such unit to rest. The slow-down switch again operates so as to speed up the motor, and, as another hoisting unit nears its limit of travel, the motor is again automatically slowed down until such hoisting unit reaches its limit of travel and the same is brought to rest, after which the motor again speeds up. This operation continues as long as there are any hoisting units operatively connected to the driving motor.

When it is required that any one or more hoisting units shall operate to lower their load, the corresponding down buttons are pushed. The various operations of different parts are similar to the operations already described in connection with raising one or more loads, with this exception,—when a down button is operated and the switch 33 is moved so as to start the motor, the circuit closed through the lower magnet winding of the push-button includes the magnet winding of the corresponding brake and down limit switch, but does not include the corresponding tripping magnet and the latter is not energized, consequently, while the brake will be released, the tripping mechanism will not permit the hoisting drum to be operatively connected to the friction driving disk on the motor shaft. The unbalanced load will, however, since the brake is released, cause the hoisting drum to turn backward, thereupon operatively connecting the hoisting drum through its corresponding clutch mechanism and sprocket to the co-operating sprocket mounted upon the motor shaft, and in this manner the lowering, as well as the raising, of the load is dependent upon the motor speed which may be varied within wide limits by means of the manually operated switch 33.

The operation of the slow-down and limit devices is similar, whether the load is being raised or lowered, and while a single switch is used to control the slowing down of the motor, whether the same is hoisting or lowering, a separate limit switch is used for the up and down motions. It is not necessary first to operate the push-buttons and then

start and accelerate the motor, but, if desired, the motor may be started and run at any desired speed within the capacity of the machine, and then any desired up or down button may be pressed, the hoisting unit corresponding thereto will raise or lower its load and automatically slow down, and finally stop at its limit of travel.

In the system of electrical control just described where the different hoisting units are hoisting and lowering at the same time, it is not possible to change the speed of hoisting without changing the speed of lowering as well. The system of electrical circuits illustrated in Fig. 2, in which two motors are used, one for hoisting and one for lowering, makes it possible to vary the hoisting or lowering speeds at will independently of each other.

Referring to Fig. 2, 80 designates the hoisting motor and 80' the lowering motor. The motor 80 is preferably of greater power than that of motor 80', for the reason that the unbalanced load upon any hoisting unit, when the same is operating to raise or lower its load, has to be raised against gravity in the case of hoisting, but assists the lowering motor 80' when it is being lowered. In actual practice it is found that the motor 80' is driven by the unbalanced descending load, and thus the motor acts as a generator, sending current back into the line and thereby providing an electro-dynamic brake of variable retardation.

The operation of the electrical system of control is substantially the same in Fig. 2 as in Fig. 1. It will be noticed that the starting resistance for the hoisting motor 80 comprises five sections controlled by five magnets 12, 13, 14, 15 and 15', also the armature parallel resistance has but two sections controlled by a corresponding number of magnets 26 and 27. The speed of this motor 80 is controlled by the switch 33 in a manner similar to that pointed out in connection with Fig. 1. The up limit switches 57, 57', etc., and the down limit switches 58, 58', etc., operate in like manner to bring any particular hoisting unit or number of units to rest as soon as each individual hoisting unit has reached its limit of travel. The same main line switch 93 supplies current to both motor controlling systems from a suitable source of electrical supply indicated by the + and - signs. It will be further noticed that in Fig. 2 there is no slow-down magnet for the hoisting motor. A slow-down magnet is, however, provided for the lowering motor 80' and is operated automatically by the slow-down switches 46', 46', etc., whenever any one of the hoisting units has operated to lower its load by means of the motor 80' almost to its lower limit of travel, shortly after which the corresponding limit switch comes into action and

brings the load to rest. The motor 80' is immediately speeded up automatically until another curtain approaches its lower limit of travel and the same cycle of operations is repeated as long as there are any hoisting units actively engaged in lowering. The speed of the hoisting and lowering motors 80 and 80' is controlled independently through wide limits by means of the speed controlling switches 33 and 33', respectively. In this manner when the hoisting apparatus is used to operate theater curtains, certain curtains may be rapidly raised while at the same time other curtains may slowly descend, or the reverse may be the case, and in this manner many beautiful scenic effects may be produced at will. The slowing down and consequent stopping of all of the curtains upon reaching their limit of travel is accomplished automatically.

While I have illustrated and described the preferred form of my invention, I do not wish to be limited to the precise construction and arrangement of parts shown, since it is obvious that various changes could readily be made in the construction and arrangement of parts by those skilled in the art without departing from the spirit and scope of my invention.

30 What I claim as new and desire to protect by Letters Patent of the United States is:—

1. In a system of electrical control, the combination with a source of current supply, of an electric motor, controlling devices for the motor, a plurality of electro-magnets, and selective devices operative respectively to effect the energization of one or both of said electro-magnets.

2. In a system of electrical control, the combination with a source of current supply, of an electric motor, motor controlling mechanism, a brake magnet, a trip magnet, and means for effecting the energization of either the brake magnet alone or both the brake magnet and trip magnet when current is supplied to the motor.

3. In a system of electrical control, the combination with a motor, of a source of current supply, motor controlling mechanism, a plurality of electro-magnets, and devices for effecting the energization of said magnets when current is supplied to the motor, one of said devices controlling one of said magnets and the other of said devices controlling both of said magnets.

4. In a system of electrical control, the combination with a source of current supply, of an electric motor, controlling mechanism for the motor, a brake magnet coil, a trip magnet coil, a circuit for the brake magnet

coil, a circuit including both of said coils, and selective devices for controlling said circuits.

5. In a system of electrical control, the combination with a source of current supply, of a motor, controlling mechanism therefor, a brake magnet coil, a trip magnet coil, circuits for said coils each open at a plurality of points, selective devices for manually closing each circuit at one point, and means for automatically completing said circuits when current is supplied to the motor.

6. In a system of electrical control, the combination with a source of current supply, of an electric motor, controlling mechanism therefor, a brake magnet coil, a circuit therefor normally open at a plurality of points, a manual device for closing the circuit at one point, and means for automatically completing said circuit when current is supplied to the motor.

7. In an electrical system of control, the combination with a source of current supply, of an electric motor, a manual controlling switch therefor, a brake magnet coil, a manually operable switch in the circuit of said coil, an electro-magnetic switch in said circuit, and means for operating said electro-magnetic switch when the controlling switch for the motor is operated.

8. In an electrical system of control, the combination with a source of current supply, of a motor, controlling means therefor, a plurality of brake magnet coils, a trip magnet coil associated with each brake magnet coil, selective devices controlling the circuits of the brake magnet coils alone, and selective devices controlling the circuits of the brake and trip coils together.

9. In a system of electrical control, the combination with a motor, of controlling apparatus therefor, a bank of push-button switches comprising a double series of electro-magnets, a series of devices controlled by said switches, a normally closed circuit for one series of said electro-magnets, means for opening said circuit when the motor circuits are closed, an additional circuit for said second series of electro-magnets open when the motor circuits are open, and means for closing said second circuit when the motor circuits are closed.

In testimony whereof, I have signed my name to this specification in the presence of two subscribing witnesses.

ANDREW M. COYLE.
